UNITED STATES PATENT OFFICE.

CHARLES H. WILLIAMS, OF CLEVELAND, OHIO, ASSIGNOR TO CLEVELAND CITY FORGE AND IRON COMPANY, OF SAME PLACE.

MACHINE FOR MAKING COUPLING-PINS.

SPECIFICATION forming part of Reissued Letters Patent No. 9,828, dated August 2, 1881.

Original No. 110,179, dated December 13, 1870. Application for reissue filed May 2, 1881.

To all whom it may concern:

Be it known that I, CHARLES H. WILLIAMS, of Cleveland, in the county of Cuyahoga and State of Ohio, have invented certain new and 5 useful Improvements in Mechanism for Making Coupling-Pins; and I do hereby declare that the following is a full, clear, and complete description thereof.

Figure 1 is a plan or top view of a machine 10 with my improvements for making coupling-pins for railroad-cars. Fig. 2 is a section to the right of the line $z z$, Fig. 1. Fig. 3 is the left-hand side of the machine. Fig. 4 is the right-hand side. Fig. 5 shows a coupling-pin 15 in successive stages of its manufacture. On Plate 3 are additional detached figures of the several dies used in the machine for making coupling-pins, which figures are enlarged views and will be referred to in description.

20 In the drawings, A is an iron bed-plate or table, which may be of the form shown, or such other as will answer the purpose, and provided with journal-boxes B B for the shaft C, which may be provided with a pulley or gear to turn it and operate the machine.

25 On the left-hand side of the plate A, I make the flange D, and on the left side of the flange the lugs E and F, for seats for the dies G H, Figs. 3, 6, and 7, which are fastened by plates 30 G' H' in place, as shown in Fig. 3.

35 The traversing yoke I is fitted to traverse on the lug E, and provided with flanges J J, arranged to traverse under the cleats J' J' when it is worked by the link I', which connects it to the cam I² on the shaft C. This yoke has the die G² fastened to it by the plate G³, which die corresponds to the die G, Fig. 6, to taper and form the points of the pins, as shown in Fig. 5.

40 The die H², Figs. 3 to 7, is fastened in the end of the yoke I by the plate H³, Fig. 3, which die H² is a counterpart of the die H, to swage the handle or top of the pins flat, as shown in Fig. 5.

45 On the top of the plate A the lug K is made to form a seat for the die K', which is fastened by the plate K², secured by bolts, as seen in Fig. 1. At the lower left-hand corner of the plate A the lug L is made with a groove under 50 its upper edge, for the flange on the traversing block L' to traverse in. This block has a

flange on the opposite edge, which traverses under the edge of the guide-block M, which is fastened to the plate A by bolts, as shown in Fig. 1.

55 The block L' carries the die K³, which is fastened to it by the plate K⁴, Fig. 1, and corresponds to the die K', Figs. 1, 12, 13. The die K³, Fig. 1, corresponds to K³, Figs. 12, 13, which dies are grooved to clamp the shaft N 60 of the pin and hold it while a portion of it is upset to form the head or collar N', one-half of this collar being formed in the countersink in the dies, as shown by dotted lines in Fig. 1, at a.

65 The traversing slide P, which works against the inside of the flange D, is held in position by a flange traversing under the edge of the block M. This slide P has its forward or lower end inclined, to correspond to an incline on 70 the block L', so that when the slide P is pushed down by the cam P' on the shaft C the block L' and the die K³ are moved toward the die K' to clamp and hold the shaft of the pin, as before stated.

75 The heading or upsetting die Q is fastened in its stock Q' by the plate Q², Fig. 1. This stock is fitted to traverse on the plate A, and has a flange on each side, one of which works under the edge of the block M and the other 80 under the edge of the guide-block M', fastened to the plate A, and it is pushed forward to carry the die Q down to the dies K' K³ by the cam Q³ on the shaft C, and is forced back by the spring Q⁴ against a lug on the side of the 85 stock Q'.

The slide P is drawn back by the rod P² and spring P³, fastened to the plate A, and the block L' is drawn back by the spring L², fastened to the lug L³, as shown in the drawings. 90

When the slide Q' is thrown back by the spring Q⁴ it is stopped by the adjusting-slide M², fastened to the block M'. By adjusting this slide M' the slide and die may be stopped, so as to graduate the quantity of iron put in 95 the collar N'. After the collar N' has been formed on the pin the dies open and the pin drops down through the opening M³ in the plate A to the right side for further manipulation.

100 The devices for swaging the neck or handle and punching it are shown in Fig. 1 and in

elevation in Fig. 4. To this end the flange R and lugs R' R² are made to project up from the right-hand sides of the lug K, and the lugs R' R² are perforated for the pin R³, which forms the fulcrums of the levers S S', which are raised by the cams S² S³ on the shaft C. (Shown by dotted lines in Fig. 4.) These levers are drawn down or against the cams and kept in contact therewith by the spiral springs S⁴ S⁵, attached to the bed-plate.

On the right-hand side of the machine the lug T is made to form seats for the die T', which is held in place by the plate T², and also for the die V, which is held in place by the guide- 15 rest V'.

The traverse-slide or die-box W is fitted to traverse between the lugs U U on the side of the flange R, and is worked by the lever S, fitted into a stud in the back of the slide W, 20 Figs. 1, 4. This slide W forms the seat for the die V², which is fastened to it by the plate V³. The dies V and V² are clamping-dies, (seen in Figs. 4, 10, 11,) which press the handle N² of the pin and keep it flat, while the dies T' T³ 25 swage or compress and narrow the neck of the handle, as shown in No. 3, Fig. 5, and remain closed around the handle while the punch V⁴ descends and punches the hole in handle and finishes the pin. The die T³ has its seat in the 30 traversing slide X, and is fastened to it by the plate T⁴. This slide traverses between the ways X' X', and is worked by the link X², which connects it to the cam X³ on the shaft C. (Shown by dotted lines in Fig. 4.) The slide 35 W has a recess or groove in its upper end, in which the block Y is fitted to traverse, and is worked by the lever S' on a stud in the side of the block.

The dies V and V² are perforated for the 40 punch V⁴, which is fastened in the block Y, and worked by it so as to punch a hole in the handle N² after it is necked and while it is clamped by the dies V V².

To make the coupling or shackle pins, I take 45 a bar of iron of the proper size and length, and heat one end thereof and put it between the dies G G², Fig. 3, to swage the point, and after the dies have closed once upon it and opened the bar is to be turned one-fourth the way 50 around and the dies allowed to close on it again, which completes the point. The other end is then heated and put in between the dies H² H to flatten the end for the handle, and while it is still hot the flat end or handle is put between the dies K' K³, into the socket in the die Q, Figs. 1, 12, 13, 14, 15. The said socket is formed to fit the flattened end, to thus preserve its shape, while the dies K' K³ clamp the bar, and the die Q moves down onto the 55 clamping-dies and upsets the bar, or that portion of it that is between the ends of the clamping-dies and the die Q, and forms the head or collar N' in the countersinks a, Figs. 13, 15, and indicated by dotted lines a in Fig. 60 1. When the collar is formed the die Q is drawn back from off the head and handle, and

the clamping-dies open and the pin falls to the ground, as set forth. It is taken up, and while the head is still hot the handle is put in between the dies V V², Figs. 4, 10, 11, which clamp and hold it flat while the dies T' and T³ 70 swage and narrow the neck of the handle, and the punch V⁴ descends and punches the hole N³ in the handle and finishes the pin.

What I claim as my invention, and desire 75 to secure by Letters Patent, is—

1. The above-described machine for making coupling-pins for railway-cars, provided with the dies H' and H² for flattening the handle, and the dies Q, K', and K³ for forming the 80 head or collar, and the dies V and V², and the dies T' and T³ and the punch V⁴ for necking the handle and punching the hole in it, substantially as described.

2. The combination of the dies H and H², 85 co-operating for flattening the handle of the pin in the manner substantially as set forth.

3. In combination with the dies K' and K³, provided with a countersink, a, the heading-die Q, also provided with an annular countersink corresponding to a of the dies K' and K³, 90 and co-operating therewith for forming the collar of the pin, substantially as described.

4. In machines for the manufacture of car-coupling pins, the perforated clamping-dies V 95 and V² and compressing-dies T' T³ and punch, operating conjointly for forming the neck or handle of the pin and punching the same, substantially as set forth.

5. In combination with the block L', carrying the die K³, the slide P, cam-spring P³, link and spring L², and link connecting said spring to the die-carrying block L', substantially as described, and for the purpose specified.

6. In combination with the stock Q', carrying the heading-die Q, the cam Q³, and spring Q⁴, for the purpose substantially as set forth.

7. With the clamping-dies V and V² and punch V⁴, the combination of the levers S and S', pivoted to the studs R' and R², with their respective cams and springs, arranged substantially as and for the purpose set forth.

8. As an improvement in the art of making car-coupling pins, forging a bar of metal by means of dies adapted thereto and applied 115 successively, so as to upset a portion of the bar near one end into a cavity of proper shape, and thus form upon it a solid collar, to flatten the extremity of the pin adjacent to the head or handle, to reduce the metal 120 lying between the collar and the head to form the neck, and to taper the opposite end of the pin to facilitate its entrance into the hole, and to hold in coupling when applied, substantially as set forth.

In evidence whereof I subscribe my name in presence of two witnesses.

CHARLES H. WILLIAMS.
